UNITED STATES PATENT OFFICE.

JAMES T. DICKSON, OF LOS ANGELES, CALIFORNIA.

TWO-CYCLE ENGINE.

1,128,234.

Specification of Letters Patent.

Patented Feb. 9, 1915.

Application filed November 11, 1913. Serial No. 800,353.

To all whom it may concern:

Be it known that I, JAMES T. DICKSON, a citizen of the United States, residing at Los Angeles, in the county of Los Angeles, State 5 of California, have invented new and useful Improvements in Two-Cycle Engines, of which the following is a specification.

This invention relates to an internal combustion engine, preferably of the two-cycle 10 type; and the invention consists particularly in certain mechanisms and arrangements whereby a simplified distribution of the combustible mixture is effected.

It is the prime object of this invention to 15 provide a mechanism for handling and distributing the combustible mixture to the cylinders, and to compress the gases for the several cylinders in such a manner that the engine operation is of high efficiency.

20 It is also an object of this invention to provide such mechanism in very simple form.

The essentials of my invention include the provision of a compression end on each of 25 the cylinders, and a special valve adapted to coöperate with the pistons in the cylinders to deliver compressed gases into a reservoir which is immediately adjacent the several cylinders. Admission of the mixture from 30 the reservoir to the several cylinders is effected by cylinder ports which are uncovered by the travel of the pistons. There being a comparatively large volume of gas 35 in the storage reservoir or chamber, the explosion end of each cylinder is thoroughly filled every time the cylinder port is opened by the piston, thoroughly expelling the burned gases and giving the explosion end of the cylinders a clean fresh charge for its 40 next stroke. Operating by this method, my improved engine attains a high degree of efficiency, and yet is of great simplicity when compared with a four-cycle engine of equal power and fuel efficiency.

45 I describe my preferred form of engine in the following specification, the same being shown in the accompanying drawings, in which,

Figure 1 is a vertical cross section of my 50 improved engine, Fig. 2 is a section taken as indicated by line 2—2 of Fig. 1, Fig. 3 is a section taken as indicated by line 3—3 of Fig. 1, Fig. 4 is a section taken as indicated by line 4—4 of Fig. 1, Fig. 5 is an enlarged 55 longitudinal section of the valve.

In the drawings the numeral 10 may des-

ignate a crank case of any desired configuration. I prefer to make the lower or compression ends of my cylinders integral with the crank case. This is shown at 11 60 in Fig. 1. The explosion cylinder proper 12 is mounted upon the crank case directly over each cylinder 11, so that the bores of the two cylinders are concentric. In my preferred form of engine I have two complete cylinders and two pistons 13. These pistons 13 are made with their upper ends to travel in the upper cylinders 12 and with their lower ends enlarged as at 14 to travel in the lower or compression cylinders 11. 70 The upper cylinders may be secured to the lower cylinders and thereby to the crank case by means of bolts 15, or by any other suitable fasteners. The upper cylinders 12 have annular shoulders 16 which fit down 75 into the lower cylinders 11 thereby insuring concentricity of the two cylinders. The lower cylinders need not be supplied with a water jacket; but the upper cylinders are supplied with the usual water jacket 17. 80 Water may be introduced and discharged by any of the usual means. Ignition of the explosive mixture in the cylinders may be effected by any of the usual means.

The pistons 13 are connected by connecting rods 20 to the crank shaft 21, the throws of the crank shaft being arranged so that one piston is at the uppermost point of its stroke while the other is at its lowermost point. One piston is always traveling 90 downwardly through its explosion stroke, thus giving a constant turning effect on the crank shaft 21. During the upward stroke of each piston gas is compressed in the lower cylinder 11. This compressed gas 95 passes out of the upper ends of the cylinders 11 through ports 25 in the lower edge of the walls of the upper cylinders 12. Mounted directly on the cylinders 12 is a combined pressure storage chamber and 100 valve casing 30, having in its upper part a pressure storage chamber 31 and in its lower part the valve casing 32. A vertical rotating valve 33 is adapted to rotate in the casing 32. A shaft 34 carries the rotating 105 valve, this shaft projecting downwardly to a coupling 35 which connects it with a shaft 36 driven by gears 37 from the crank shaft 21. These gears rotate the valve at even speed with the crank shaft; so that the 110 valve makes a complete revolution for each complete revolution of the crank shaft.

The upper end of the valve opens directly into the pressure storage chamber 31; and the lower end of the valve opens to the passage 38 through which mixture is drawn from the carbureter 39. The valve has two lateral ports 40 and 41 and an interior web 42 is so placed that port 41 connects with the upper open end 44 of the valve while the port 40 connects with the lower open end 45. 5

10 Mixture may be drawn through the valve through the port 40 from the carbureter 49. Compressed mixture may be forced through the valve through the port 41 up into the storage chamber 31. The casing 30 has 15 ports 46 which register with the cylinder ports 25, one port 46 on each side of the valve 33. These ports 46 are widened lengthwise of the valve, as at 46^a, and are adapted to be registered by the ports 40 and 20 41 of the valve.

When the port 40 of the valve registers with one of the ports 46^a, then the corresponding piston may draw in explosive mixture from the carbureter; when the port 41 registers with the port 46^a then one of the 25 pistons may force compressed mixture into the storage chamber 31. The valve 33 is so timed that it correctly coöperates with the pistons. For instance, the piston 13 in Fig. 30 1 is shown at the bottom of its stroke ready to commence its up stroke to compress the explosive mixture. The port 41 of the valve is just about to make connection with the port 46^a connecting to that cylinder, allowing that piston to compress explosive 35 mixture into the chamber 31. At the same time, the other piston is just beginning its down stroke, and the lower cylinder 11 of that piston is just about to be connected by 40 the port 40 with the carbureter 39, so as to draw in explosive mixture. The ports are so proportioned that these said connections are cut off at the ends of the respective up and down strokes of the pistons. When the 45 pistons reverse their movement, the valve 33 has progressed to a point where its ports 40 and 41 connect oppositely to the connection as just described; that is, port 40 will then connect to the cylinder shown in Fig. 1 while 50 its piston 13 is on its down stroke, while port 41 will connect to the other cylinder while its piston is on its up stroke. The result of this operation is seen to be the continuous compression of explosive mixture 55 into the chamber 31. The chamber 31 is connected by ports 50 directly into the lower ends of the upper cylinders 12. The ports 50 are positioned so that they are opened by the pistons 13 at their lowermost points of 60 travel, as shown in Fig. 1. The ports 50 are of ample size to allow quick passage of the compressed gases from the chamber 31 into either cylinder. The piston 13 on its down stroke uncovers exhaust ports 51 and the exhaust gases are led into the atmosphere 65

slightly before the inlet of fresh mixture from the chamber 31. By the time the port 50 opens, the pressure on the exhaust gases has been relieved; and the inrush of fresh gases over the piston head cleans out the exhaust gases and supplies the cylinder with a fresh charge, completely filling the cylinder. On the up stroke of the piston, the gases are compressed ready for firing. Each piston acts alternately, one being in its compression stroke while the other is in its firing stroke. 70

75 My preferred construction includes the essentials herein described. It is one of the particular features of this invention that a single rotary valve effects the complete distribution of gaseous mixture for a pair of cylinders. It is also a particular feature that the two compression units compress into a single common reservoir from which each 80 of the explosion cylinders is fed. The effective areas of the cylinders 11 may be equal to or greater than the areas of cylinders 12. These areas may be so proportioned that the cylinders 12 are always supplied with a full 90 charge of explosive mixture at an adequate pressure, say at or slightly above atmospheric pressure. The simplicity of my device is another feature to which I draw special attention. The casing 30 for the valve 95 33 and for the storage chamber 31 is mounted directly upon the cylinders 12, so that the cylinders form the back face of the chamber 31, as is best shown in Fig. 1. The casing 30 does not join directly with the cylinder 11 100 at any point, the ports 25 to the cylinder 11 being led through the walls of the cylinders 12.

105 Having described my invention, I claim:

1. In combination, a crank case, a pair of compression cylinders thereon, an explosion cylinder above each compression cylinder, said explosion and compression cylinders being non-integral and the lower edges of the explosion cylinders forming heads for the compression cylinders, a piston in each set of cylinders, each piston having an upper portion fitting the upper explosion cylinder and a lower portion fitting the lower compression cylinder, there being a port through 110 the wall of each of the explosion chambers communicating below with the compression cylinder and emerging in the outer face of the explosion cylinder, a port above each of said first mentioned ports leading through the wall of each explosion cylinder said port adapted to be uncovered by the downward travel of the corresponding piston, a casing secured directly to the upper explosion cylinders only and inclosing a pressure storage chamber in immediate connection to the last mentioned ports of both cylinders, an intake passage at the lower part of said casing and a valve in said casing adapted to alternately connect each compression cylinder 115 120 125 130

port to the intake passage and to the pressure storage chamber.

2. In combination, a crank case, a pair of compression cylinders thereon, an explosion cylinder above each compression cylinder, said explosion and compression cylinders being non-integral and the lower edges of the explosion cylinders forming heads for the compression cylinders, a piston in each set of cylinders each piston having an upper portion fitting the upper explosion cylinder and a lower portion fitting the lower compression cylinder, a port extending out from each compression cylinder through the wall 10 of the explosion cylinder above and emerging in the outer face of the explosion cylinder, a port above said first mentioned port leading through the wall of each explosion cylinder, said port adapted to be uncovered by the downward travel of the corresponding piston, a casing secured directly to the upper explosion cylinders only and inclosing a pressure storage chamber in immediate connection to the last mentioned ports of both cylinders, said casing being open on the side toward the explosion cylinders and the walls of said cylinders forming a wall of said compression chamber, an intake passage at the lower part of said casing, a vertical cylindrical valve casing within said chamber casing having its upper end open to said chamber its lower end open to said intake passage and having two oppositely disposed ports in its walls connected respectively with the compression cylinder ports, and a rotating hollow cylindrical valve in 15 said valve casing having oppositely disposed ports through its walls adapted to register with said casing ports and having a diagonal web extending across its interior from above one port to below the other. 20

4. In combination, a pair of cylinders and a piston in each cylinder, means for causing coöperation of the pistons, each cylinder having an upper explosion and a lower compression end, there being a compression port 25 leading out from the compression end of each cylinder and there being an intake port leading into each explosion end to be uncovered by the piston in its travel therein, a casing secured against the sides of the 30 cylinders, the side of the casing adjacent the cylinders being open so that the cylinders form one wall of a storage chamber of which the casing forms the other walls, said intake ports communicating directly with said chamber, a horizontal partition wall in the casing dividing off lower compression passages from the said storage chamber, said compression passages registering with said compression ports, a cylindrical valve casing 35 formed in said chamber casing, said valve casing having ports connecting with the compression passages and having one end open to said storage chamber, induction connection with the other end of the valve casing, a rotary hollow cylindrical valve having a transverse partition and having open 40 ends and lateral ports adapted to register with said valve casing ports, and means to cause coöperation of said valve and said 45 pistons. 50

3. In combination, a crank case, a pair of compression cylinders thereon, an explosion cylinder above each compression cylinder, said explosion and compression cylinders being non-integral and the lower edges of the explosion cylinders forming heads for the compression cylinders, a piston in each set of cylinders, each piston having an upper portion fitting the upper explosion cylinder and a lower portion fitting the lower compression cylinder, a port extending out from each compression cylinder through the wall of the explosion cylinder above and emerging in the outer face of the explosion cylinder, a port above said first mentioned port leading through the wall of each explosion cylinder, said port adapted to be uncovered by the downward travel of the correspond-

ing piston, a casing secured directly to the upper explosion cylinders only and inclosing a pressure storage chamber in immediate connection to the last mentioned ports of both cylinders, said casing being open on the side toward the explosion cylinders and the walls of said cylinders forming a wall of said compression chamber, an intake passage at the lower part of said casing, a vertical cylindrical valve casing within said chamber casing having its upper end open to said chamber its lower end open to said intake passage and having two oppositely disposed ports in its walls connected respectively with the compression cylinder ports, and a rotating hollow cylindrical valve in 55 said valve casing having oppositely disposed ports through its walls adapted to register with said casing ports and having a diagonal web extending across its interior from above one port to below the other. 60

4. In combination, a pair of cylinders and a piston in each cylinder, means for causing coöperation of the pistons, each cylinder having an upper explosion and a lower compression end, there being a compression port 65 leading out from the compression end of each cylinder and there being an intake port leading into each explosion end to be uncovered by the piston in its travel therein, a casing secured against the sides of the 70 cylinders, the side of the casing adjacent the cylinders being open so that the cylinders form one wall of a storage chamber of which the casing forms the other walls, said intake ports communicating directly with said chamber, a horizontal partition wall in the casing dividing off lower compression passages from the said storage chamber, said compression passages registering with said compression ports, a cylindrical valve casing 75 formed in said chamber casing, said valve casing having ports connecting with the compression passages and having one end open to said storage chamber, induction connection with the other end of the valve casing, a rotary hollow cylindrical valve having a transverse partition and having open 80 ends and lateral ports adapted to register with said valve casing ports, and means to cause coöperation of said valve and said 85 pistons. 90

In witness that I claim the foregoing I have hereunto subscribed my name this 22nd day of October, 1913.

J. T. DICKSON.
